UNITED STATES PATENT OFFICE

CHARLES FRANCIS JENKINS, OF WASHINGTON, DISTRICT OF COLUMBIA, ASSIGNOR
TO JENKINS LABORATORIES, OF WASHINGTON, DISTRICT OF COLUMBIA, A COR-
PORATION OF THE DISTRICT OF COLUMBIA

CONTROLLED-APERTURE SCANNING DISK

Application filed June 8, 1927. Serial No. 197,453.

This invention relates to the electrical transmission of motion pictures, and has for its particular object means for scanning a picture surface with multiple pencils of light controlled separately.

5 Powerful searchlights are now available, fitted with objective lenses which project long distances. A light-intercepting stencil located at the back focus of the lens is imaged 10 on clouds or other distant "screens." The stencils may be pictures, letters, legends, or the like, and such make attractive advertising. If these pictures had life-like motion, their attractiveness and publicity value would 15 be greatly enhanced.

But obviously the heat of the searchlight beam is so enormous that the usual picture-carrying film would instantly vaporize. It is, therefore, necessary to employ other 20 means. This is attained in the present invention by interposing an indestructible scanning disk in the light beam, and building up the projected picture by opening and closing the apertures of the disk by a master motion 25 picture.

With this and other objects in view the invention consists in the novel details of construction and combinations of parts more fully hereinafter disclosed and particularly 30 pointed out in the claims.

In the drawings like symbols refer to like parts in which Fig. 1 is an elevation of the projector; Fig. 2 a schematic drawing of the master control picture mechanism; Fig. 3 the 35 scanning disk, and Figs. 4, 5 and 6 details of the several mechanisms.

In the figures, A is a searchlight, trun- 40 nioned in a frame B. C is a latticed frame-work attached to the lamp and extending in the direction of the light beam. This lat- 45 ticed frame carries at its far end a lens D. In the back focus of the lens is a rotary scanning disk E, driven by a motor F.

On the scanning disk each aperture is 45 closed by shutters G (Fig. 3), mounted on pivots G¹ (shown in detail in Figs. 4, 5 and 6), with bell-crank attachment to rod G². The lower crank end of G² engages with the bar H of the armature J of the electro-magnet K.

50 There are six of these magnets, duplicates

of the H—J—K unit, a magnet unit for each aperture of the six apertures of the radial rows of apertures. Each H—J—K unit is stationarily fixed. As each row of bell-crank passes these magnets each of the six 55 aperture shutters is opened by its particular magnet-armature bar H for so long as light is needed through that aperture to build up the motion picture projected on the clouds.

The six magnets are attached by wires to 60 brushes M, one magnet to each brush. These brushes bear upon six adjacent rings of commutator segments N, eight segments to each ring. These segments are connected by wire O to six corresponding brushes P on disk Q. 65 The rotation of the disk sweeps these brushes P over the face of each of the "frames" R of the motion picture "ribbon" S.

The individual frames are each a zinc etching, or other suitable master frame, and the 70 brushes sweeping over the face of these frames make contact with the high parts of the picture to close an electric circuit, the return wire of which is common to all.

Each of the several frames of the motion 75 picture series differs from adjacent frames, much as the frames of cartoon film do, so that these several frames projected on the clouds in rapid sequence, as explained below, produces the illusion of motion pictures.

80 The operation of the device is as follows:— The arc being struck, and the motor started, the rotating scanning disk intercepts the light beam except where the apertures are opened by the electro-magnet unit H—J—K activated by the current through the brush contacts on the zinc etching to build up a motion picture in the "sky." Thus—

The brush-carrying disk Q, and the scanning disk E rotate synchronously. The high 85 spots of the picture of each frame R sends current through the proper electro-magnet, pulling down the bar H (to the dotted position, Fig. 6) to open the corresponding aperture of the scanning disk, permitting light to 90 reach the cloud "screen" at the proper time, and thus build up a fac-simile picture.

95 While corresponding aperture shutters G of each radial group on the scanning disk are placed at different radial distances, the lower 100

crank-ends of the shutter-operating rods G^2 are on a circle common to the same shutter of all the eight radial groups. This permits the employment of a single electro-magnet for corresponding shutters of each radial group, so that but six electro-magnets are required to open and close all the shutters.

The armature bar H is of a length which permits holding open each shutter in succession for the full width of the picture scanning movement.

Obviously I do not wish to limit myself to the employment of only the mechanism shown, for this could be modified. But any multiple light-beam intercepting device which can be so controlled by a master record to reproduce the record at the distant plane of contact of the beam would answer.

The word light-pencils is used herein to distinguish the light which passes the scanning apertures, the composite of which make up the light-beam.

What I claim, is:

1. The combination of a light-beam projector, and rotary intercepting means having apertures, and means for opening and closing said apertures for permitting the passage of said light-beam for only predetermined areas, and times.
2. The combination of a light-beam projector, rotary intercepting means having apertures, and means carried by the rotary intercepting means for covering and uncovering said apertures for permitting the passage of said light-beam for only predetermined areas and times, and a master control means connected to said intercepting means for giving a definite order to said projection areas and times.
3. A multiple-apertures rotary scanning disk, and means carried by said disk for closing and opening said apertures separately.
4. A multiple-apertured rotary scanning device, and shutters carried by said device in the rotation thereof for limiting the light which may pass each aperture.
5. In a scanning apparatus, the combination of a plurality of sets of light valves, means for determining the order in which each set is to be effective in scanning, and means for operating predetermined valves in each set.
6. In a scanning apparatus, the combination of a plurality of sets of light valves, means for determining the order in which each set is to be effective in scanning, and electrical means for variably operating one or more valves in each set.
7. In an image reproducing system means comprising a plurality of sets of image analyzers, each set adapted successively to traverse the image, and means including a plurality of sets of light valves controlled by said analyzers, and means for bringing

each set of light valves in operation in cyclic order.

8. In an image reproducing mechanism a light beam, a plurality of sets of light valves, each set adapted to be moved in succession across said beam, means for rendering each set effective only as it is crossing said beam, and means including a traveling picture film for controlling the effectiveness of each valve in the particular set that is crossing said light beam.

9. The combination of a surface having electric-current-contacting graphic representations thereon, scanning means comprising a plurality of circuit terminals contacting successively with said scanned surface, a light beam electrically controlled by said contacting terminals, and a perforated scanning disk having a plurality of sets of light valves, means for rotating said disk to cause each set of light valves to traverse said beam in succession.

In testimony whereof I have affixed my signature.
